SIGN CHARACTER

Joseph T. Cochran, Chicago, Ill.

Application August 17, 1931, Serial No. 557,536

7 Claims. (Cl. 40—141)

This invention relates in general to a sign for advertising or display comprising letters or characters made of glass or other transparent material and having a rear surface which forms a reflector either of itself or by the addition of reflecting material thereto so that the character has a brilliant reflecting appearance.

One of the principal objects of the invention is in the provision of a sign character composed of transparent material either plain or colored and adapted to resemble an electrified gas filled tube.

A further object of the invention is in the provision of a sign character which is highly reflecting and adapted to glow when illuminated by natural or artificial light.

A further object of the invention is in the provision of a sign character having a reflecting surface made up of a great number of relatively small projections or indentations which together form a reflecting surface visible through a wide angle from the front thereof.

A still further object of the invention is in the provision of a sign character in which a great number of reflecting surfaces at the back are magnified by a lens portion running with and at the front of the character and reflected thereby through a wide angle at the front.

A still further object of the invention is in the provision of a reflecting letter or character which is simple and inexpensive, not likely to break or become damaged, and easily applicable for display purposes whether illuminated or not.

Other objects of the invention will appear hereinafter, the accompanying drawing illustrating various forms and the preferred embodiment of the invention.

In the accompanying drawing,

Fig. 1 represents a letter constructed in accordance with this invention;

Fig. 2 is a section of a letter or character;

Fig. 3 is a similar section presenting a plane reflector spaced from the rear of the reflecting surface;

Fig. 4 shows a similar section with a curved reflector at the rear of the character;

Fig. 5 shows a section with a front lens portion and a rear convex surface;

Fig. 6 shows a front convex lens portion and a rear concave reflecting surface;

Fig. 7 shows a section with a front convex lens portion; a rear reflecting surface and a reflecting material applied to the back of the reflecting surface;

Fig. 8 is a section of a character showing a slightly concave rear surface which is the result of natural shrinkage of a material such as glass in hardening or setting from a rear plane surface;

Fig. 9 represents an angular prismatic reflect-

ing surface which may be produced at the rear of the letters or characters instead of the circular forms; and

Fig. 10 is an enlarged sectional detail illustrating the application of the reflecting material and a protecting coating to the reflecting surface.

This invention relates to the formation of sign letters or characters by a process similar to that disclosed in my application Serial No. 467,855 filed July 14, 1930 with the provision of the innumerable reflecting surfaces directly at the back of the glass or other material of which the letters are formed. This may be accomplished by providing the letter forming device or roller with depressions which will make the desired reflecting surfaces at the back of the letter or character as it is formed.

Referring now more particularly to the drawing, a letter or character 11 is shown in Fig. 1 which is represented as having an outwardly rounded lens front running with the letter or character and an innumerable number of regular reflecting lenses formed directly in the back of the letter and preferably circular in form although they may be hexagonal or diamond shaped as suggested in connection with Fig. 9.

When viewed from the front, a letter so formed with innumerable reflecting surfaces at the back presents a brilliant appearance even under ordinary light and brightly shines or glows if illuminated with a bright light. If the glass or reflecting surface at the rear is colored, the reflection is correspondingly colored and is brilliant or flaming, depending upon the color. Circular reflectors at the back of a letter which is rounded at the front appear elongated or oval depending upon the shape of the letter and it is extremely difficult to produce a letter having the same brilliance of reflection throughout the entire letter. It can be produced only by carefully applying the reflection surfaces to the letter so that they are even and uniform throughout with the same transverse contour and depth of depressions. If the depressions are not uniform the letter will have a so-called "dark spot" which does not uniformly reflect the light.

In the cross sectional body structure 13 as illustrated by Figs. 2, 3 and 4, the outer or lens portion 14 is rounded outwardly less than a semi-circle and the back has a straight reflecting surface in which are a number of circular reflecting surfaces 15 convex at the back. In attempting to make this structure of glass it is found that the transverse surface of the letter at the back will not be a straight line but due to the natural shrinkage of the material it will form a slightly concave rear surface as indicated in Fig. 8.

It is found that the circular rounded reflecting

surfaces will reflect the light almost perfectly around their edges but at their center there is a tendency to refract the light. To counteract this tendency a reflector 16 is added which bears 5 against the reflectors 15, as shown in Fig. 13, or a reflector 17 also running with the letter and curving transversely outward may be attached to the edges thereof as shown in Fig. 4.

10 Instead of the rear surface of a letter being flat at the back, the body of a letter 18 may be convex at the back as shown in Fig. 5 or a body 19 may be concave as shown in Fig. 6.

15 It is also found that to provide the outer lens or running surface of a letter with an additional row of circular lenses 20 or a plurality of circular or angular lenses 21, as shown in Fig. 7, will localize and produce additional magnification and dispersion of the reflections which produces a more striking effect.

20 For certain distances the outer running lens will be less than a semi-circle in cross section or more than a semi-circle or substantially a semi-circle. In small letters less than an inch in height, for example, it is found that very poor results are obtained unless the cross sectional body of the lens is less than a semi-circle.

In a semi-circular glass body 22 as shown by Fig. 8, the actual depression 33 due to the natural shrinkage of the glass in hardening or settling is an appreciable curve.

In forming letters of this kind of glass by rolling or otherwise pressing them in a mold there is usually a thin adhering body of glass at the back of the letter which must be broken from the edge to clear up the letter. This edge tends to be rough or jagged, and to make a smooth letter, a portion of the edge 23 is ground at the

same or a different inclination to the surface of the adjacent rear reflectors 24 of a body 35. 40 In the enlarged view of Figure 10 there is a reflecting ring 25 approximately below the line 26 which reflects practically all of the light. The rounded surface 27 above the line 26 only par-

45 tially reflects the light and it is necessary there-
fore to provide a reflecting covering or coating
28 such as aluminum foil, tinfoil, or silvering, in
order to obtain the best reflection. If the join-
ing edges or grooves 29 of the reflecting surfaces
are sharply defined it is difficult to make this

reflecting surface 28 fit therein and in practice it assumes a position as shown in Fig. 10 not clearly seated in the bottoms of the grooves 29. It does however fit the reflecting surface above the line 26 and thereby returns the reflection of that portion above the line 26. To protect

the reflecting material 28, a coating 30 of paint or lacquer is applied to the back of the reflecting material 28 and overlaps it at the edge of the letter preferably at the ground edge 23 thereof so that the edges of the reflecting material are thus protected and covered.

Instead of a circular reflector, the reflecting surface 31 may be angular as indicated in Fig. 9.

In producing and using a letter of this kind the letter may be provided only with a reflecting surface consisting of innumerable reflecting surfaces at the back thereof or these reflecting surfaces may be covered or partially covered by reflectors; the back may be straight or curved; and the front lens may be curved more or less than a semi-circle and also provided with additional lenses in or on the body of the main lens which runs with the letter.

I claim:

1. A sign character having a transparent body which constitutes the character with a smooth and continuous front convex lens portion running with and extending continuously throughout the character and a back reflector therefor formed in the body and comprising staggered rows of small closely spaced circular or parabolic projections covering the rear of the body and each substantially spherical in form and the rounded portion extending oppositely to the curvature of the front lens portion, whereby the front lens acts as a condenser of entering light over the area to be reflected, magnifies the reflectors, and disperses the light reflected therefrom over a wide angle at the front of the character simulating a character composed of illuminated gas filled tubing.

2. A glass sign character in accordance with claim 1 in which the small rounded spherical reflectors form a continuous back surface which is substantially flat and continuous but in cross section is slightly concave due to the greater shrinkage of the glass at the center. 20

3. A sign character having a glass body constituting the entire character with a convex lens front running with the character and with a substantially flat back reflector which consists of innumerable small spherical projections spaced closely together and staggered to entirely fill the back surface, each forming a tiny reflector for the light which enters the front lens, the reflectors being so small and so close together that they produce a uniform brilliant character reflected in a wide angle at the front of the character simulating an illuminated gas filled tubing character. 35

4. A sign character in accordance with claim 3 in which the small spherical projections are coated at their rear surface with a reflecting medium which accentuates the brilliance of the reflection as viewed from the front of the character so that it responds to natural and artificial illumination from the same side. 40

5. A sign character in accordance with claim 3 in which the front lens portion has individual lens projections from the surface thereof and formed of the body of the glass to accentuate the reflection at these locations. 45

6. A sign character of glass having a body 50
which constitutes the character only, comprising
a front convex lens portion running with the
character and a reflector back with innumerable
circular depressions therein forming closely
spaced spherical projections convex rearwardly 55
and opposed to the curvature of the front lens,
and a reflecting medium covering the backs of
the projections but not extending into the ex-
treme angles of the depressions between them
simulating an illuminated character of gas filled 60
tubing.

7. A sign character in accordance with claim 6 in which the edges of the back are rounded off, the reflecting medium extending nearly to the extreme edges thereof, and a protective coating 65 extending over the reflecting medium and to the extremities of the rounded off edges thereby widening the angle of reflection and more resembling an illuminated gas filled tubing lamp.
